(57) **CLAIM**

The ornamental design for a wearable electronic device, as
shown and described.

DESCRIPTION

FIG. 1 is a front perspective view of a wearable electronic device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

(Continued)

FIG. 9 is a cross-sectional view taken through line A-A of FIG. 2; and,

FIG. 10 is another cross-sectional view taken through line A-A of FIG. 2 in which a band or string is shown to provide example environment.

The dashed broken lines in the drawings illustrate example environment and portions of the wearable electronic device that form no part of the claimed design.
